UNITED STATES PATENT OFFICE

2,505,187

HYDRAULIC JACK

Edwin C. Juergens, Chicago, Ill.

Application December 6, 1946, Serial No. 714,549

8 Claims. (Cl. 254—134)

1

This invention relates to improvements in hydraulic lifting jacks of the kind used for automotive vehicles, although not necessarily limited to such use.

Among the objects of the invention is to provide a simple and dependable hydraulic ram and a self-contained double acting pump mechanism for operating the same which can be readily manipulated by hand with a minimum of effort.

Another object is to provide a simplified and improved form of universal mounting for the bumper catch on the lifting column to permit the latter to accommodate itself automatically to tilting movements of the bumper or other portions of the car with which it is engaged, thereby relieving the lifting column of the jack from excessive lateral bending stresses.

A further object is to provide an improved form of mounting for the bumper catch support, permitting selective adjustment of the latter at various points along the lifting column of the jack.

Other objects and advantages of my invention will appear from time to time as the following description proceeds:

The invention may best be understood by reference to the accompanying drawings, in which:

Figure 1 is a side view of a lifting jack constructed in accordance with my invention, with a portion of the lifting column broken away;

Figure 2 is a vertical section of the upper part of the jack showing details of construction of the pump mechanism and drawn to a larger scale than Figure 1;

Figure 3 is a vertical section of the lower end of the jack drawn to the same scale as Figure 2, showing details of construction of the bumper catch and the lower end of the lifting column;

Figure 4 is a detailed section of the bumper catch support taken on line 4—4 of Figure 1;

Figure 5 is a detailed section taken on the broken line 5—5 of Figure 4;

Figure 6 is a fragmentary perspective detailed view of the bumper catch and a portion of the trunnion strap associated therewith;

Figure 7 is a detailed perspective view showing the top and one end of the saddle nut forming part of the bumper catch support;

Figure 8 is a detailed perspective view showing the bottom and one end of the saddle nut shown in Figure 7; and

Figure 9 is a perspective view of a lock spring for adjustably holding the saddle nut on the lifting column.

Referring now to details of the embodiment of

2

my invention illustrated in the drawings, the lifting jack indicated generally at 10 comprises as its main elements a telescope lifting column 11, a bumper catch 12, a hydraulic pump 13 at the top of said column, and a socketed foot member or pedestal 9 at the bottom of said column.

The lifting column 11 consists of an elongated ram cylinder 15 with a ram rod 16 reciprocally mounted therein, said ram rod having a piston head 17 at its upper end. The lower end of the ram rod extends through a suitable bushing 18 threaded in the bottom end of the ram cylinder and having suitable packing means herein comprising an O-ring 19 fitting into an interior annular groove 20 in the bushing 18. The pedestal 9 may be permanently secured to the bottom end of the ram rod by a ring 9a passing loosely through a hole 16a near the base of said ram rod and also passing through holes 9b, 9b in said pedestal. The upper end of the ram cylinder 15 is externally threaded on a lower extension 21 of a pump cylinder 22, which will hereinafter be more fully described.

The exterior surface of the ram cylinder 15 is formed with a plurality of longitudinal spaced annular grooves 25, 25 adapted to provide supporting abutments for the selective adjustment of the bumper catch 12 which will now be described.

The bumper catch indicated generally at 12 includes a C-shaped jaw 26 with parallel side walls 27, 27, mounted for universal tilting movement with respect to the lifting column 15 in a manner somewhat similar to and broadly disclosed in my earlier application, Serial No. 657,796, filed March 28, 1946. The jaw 26 has a lower forwardly projecting portion provided with a plurality of notches 28, 29, 30, and 31, arranged to permit said bumper catch to accommodate itself to automobile bumpers of different sizes and shapes when the lower edge of the bumper is engaged in one of said notches.

The side walls 27, 27 of the jaw 26 are spaced apart in parallel relationship and are joined at the forward end as by bending a single strip of metal intermediate its ends, as shown. The two side walls 27, 27 curve upwardly and forwardly and terminate in spaced abutments 32, 32 disposed upwardly and generally inwardly of the notches 28, 29, 30, and 31 in the lower part of the jaw, as shown in Figure 1.

The jaw 26 is pivotally mounted on a trunnion strap 35 which consists of a sheet metal piece arched over a saddle nut 36 and having opposite upright side walls 37, 37 with outwardly extend-

ing studs 38 to which the side walls 27, 27 of the C-shaped member are pivotally connected. In the preferred form shown, the studs 38, 38 are produced by punching apertures in the side walls 37 of the trunnion strap and flanging the margins of said apertures outwardly, as shown in Figures 1, 4, and 5. After the side walls 27, 27 of the C-shaped member 26 are pivotally mounted on the studs 38, the outer ends of the latter are placed outwardly at 39, 39, to hold the C-shaped jaw permanently in pivoted relation on said studs.

The central arched portion of the trunnion strap indicated at 40 is provided with an aperture 41 through which the lifting column 15 projects with sufficient clearance at opposite sides thereof to permit lateral rocking movement of the trunnion strap relative to said lifting column.

The saddle nut 36 shown in detail in Figures 7 and 8 is generally cylindrical in form, with a bore 45 extending therethrough at right angles to the axis of said nut. The lifting column 15 projects through the bore 45 with a relatively easy sliding fit.

The arched portion 40 of the trunnion strap fits over the curved upper surface of the saddle nut 36, so as to permit limited rocking movement of the trunnion strap relative to the saddle nut on a horizontal axis. Since the jaw 26 has rocking movement with respect to the trunnion strap on a horizontal axis at right angles to the axis of said saddle nut, the jaw 26 has substantially universal tilting movement with respect to the lifting column 15.

In initially applying the jack to an automobile bumper, the lower edge of the bumper is engaged in one or the other of the notches 28, 29, 30 or 31, and then by the relatively slight tilting movement of the jaw caused when the jack starts to raise, the upper portion of the bumper will become engaged against the abutment 32 of the jaw so as to lock the bumper against further tilting movement with respect to the jaw. Thus, in effect, the bumper will become a rigid extension of the jaw 26, and the load on the bumper will be transferred to the center line of the lifting column of the jack, so that the latter will be relieved of bending stresses which would otherwise be imparted thereto.

A pair of retaining lugs 48, 48 are turned inwardly at the diametrically opposed front and rear edges of the side walls 37, 37. Said lugs normally are spaced a slight distance from the front and rear faces of the nut 36 at a point above the axis of the pivot studs 38, 38 so as to hold the nut loosely centered relative to the trunnion strap. A second pair of lugs 49, 49 are bent inwardly and then reversely at an acute angle from the front edges of the side walls 37, 37 of the trunnion strap below the lugs 48, 48, so as to extend beneath the rear of the saddle nut, as shown in Figures 4 and 5. The lugs 49, 49 have a substantial clearance below the saddle nut so as to retain it loosely between the side walls 37, 37 of said trunnion strap, but permitting limited lateral rocking movement of the trunnion strap on said nut.

The saddle nut 36 is adjustable to various positions along the supporting column 11 by means of a lock spring 55 which is adapted to be selectively engageable in any one of the plurality of annular grooves 25, 25 disposed in spaced relation along the ram cylinder 15. The lock spring 55 consists of a relatively flat length of wire with its central portion 56 looped so as to form almost

a complete circle, but terminating with relatively straight portions 57, 58. One of the terminal portions 57 is slightly offset with respect to the other portion 58 so that said straight portions may cross each other in parallel planes as shown in Figure 9. The free ends of the straight portions 57 and 58 may be bent at right angles to the plane of the circular portion 56 to form finger pieces 57a and 58a respectively.

The looped portion 56 of the lock spring 55 is normally of such diameter as to fit under slight tension in any one of the grooves 25, with its periphery projecting beyond the outer surface of the ram cylinder 15 so as to form an abutment upon which the lower face of the saddle nut 36 is supported. As shown in Figure 8, the rounded bottom surface of the saddle nut is preferably cut away toward one end thereof to form a substantially flat surface 60 surrounding the central bore 45 in the saddle nut, but leaving a semi-circular recess defined by a depending shoulder 61 at the opposite end of the nut, in which the looped portion 56 of the lock spring fits.

The arrangement just described is such that the lock spring may be applied to any one of the annular grooves 25, on the lifting column depending upon the initial vertical position desired for the bumper catch. In applying the lock spring, the thumb pieces 57a, 58a are arranged to project rearwardly between the spaced side walls 27, 27 of the C-shaped clamp 26, as shown in Figure 5. The saddle nut 36 may then be lowered until the bottom face 60 of said saddle nut engages the lock spring as shown in Figures 3 and 4. In this position it will be observed that the depending semi-circular shoulder 61 surrounds the forward end of the looped portion 56 of said lock spring so as to prevent the latter from becoming accidentally displaced from its groove 25 whenever there is any load imposed on the saddle nut. Moreover, it is necessary to lift the saddle nut with its depending shoulder 61 out of registering relation with the lock spring whenever it is desired to readjust the position of the lock spring into another groove 25. Such readjustment can then be readily accomplished by compressing the finger pieces 57a, 58a a sufficient distance to release the looped portion 56 of the lock spring and then sliding the latter along the ram cylinder 15 to a new registering position in another groove 25. By releasing the thumb pieces 57a, 58a the tension of the lock spring will cause it to become seated in the desired groove, ready to serve as an abutment for the saddle nut in its newly adjusted position.

Referring now to the hydraulic pump mechanism indicated generally at 13, the pump cylinder 22 extends upwardly in alignment with the ram cylinder 15 with which it is connected as previously described. Said pump cylinder is surrounded by a substantially concentric cylindrical casing 65 with a bottom plate 66 and a cover plate 67 which together define a chamber 68 forming a liquid supply tank or reservoir for the pump. In the form shown herein, the bottom plate 66 of the tank has a central aperture 69 through which the lower extension 21 of the pump cylinder extends. Said bottom plate is secured in place between a downwardly facing shoulder 69 on the pump cylinder and the upper end of the ram cylinder 15 when the parts are in assembled position as shown in Figure 2.

In the form shown herein the lower end of the cylindrical casing 65 fits around a flanged ram 66a of the bottom wall 66 with a suitable flexible

seal such as an O-ring 66b interposed therebetween. The upper end of said cylindrical casing fits around the lower periphery of the cover plate 67 with a suitable packing member such as an O-ring 67a interposed therebetween.

The pump cylinder 22 has an axial cylinder bore 70 opening to its upper end within which is threaded a depending sleeve portion 71 of the cover plate 67. Said cover plate has an axially extending bore 72 through which the piston rod 13 of the pump projects. Said piston rod is of substantially smaller diameter than the bore 70 of the pump cylinder and has a piston 74 at its lower end. The arrangement is such that the piston rod and its piston define a variable pressure chamber 76 in the bore 70 below the piston head 74, and a second variable pressure chamber 77 of reduced cross-sectional area in the space above the piston 74 between said piston rod and the side walls of the cylinder bore 70.

The piston rod 73 at its upper end is pivotally connected to a pump handle 74. Said pump handle is rockably supported on top of the cover plate 67 by means of a link 75 which is pivoted at its lower end on a pin 76 in a recess 77 and at its lower end to a pivot pin 78. The arrangement is such that the link 75 provides a floating fulcrum for the pump handle so that the piston rod 73 may reciprocate axially of the pump cylinder while the pump handle is being manipulated.

The pump cylinder 22 has an inlet port 80 at its bottom end communicating through a vertical passage 81 and an intersecting horizontal passage 82 with the lower end of the liquid tank 68. In the form shown herein the vertical passage 81 is formed by drilling a bore 83 longitudinally of the lower extension 21 of the pump cylinder and inserting a plug 84 intermediate the ends of said bore. The plug 84 also forms a seat for a spring pressed check valve 85 in the passage 81 which permits flow of liquid by suction into the lower chamber 76 of the pump cylinder from the reservoir 68 but preventing the flow of liquid in the opposite direction.

The piston 74 has a port 87 opening to its bottom face and communicating with a laterally opening passage 88 leading to the upper side of said piston. The port 87 is normally closed by a spring pressed check valve 89 so as to permit liquid to flow from the chamber 76 below the piston into the chamber 77 above said piston but preventing the flow of liquid in the opposite direction.

The pump cylinder has an outlet port 90 opening from its upper end and leading through an upright passage 91, and an offset passage 92 below the bottom of cylinder bore 70 into a discharge passage 93 extending through the lower extension 21 of the pump cylinder. A spring pressed check valve 95 is mounted in one of the passageways just mentioned, as for instance in the passage 93 so as to permit the flow of liquid from the upper chamber 77 of the pump cylinder into the upper end of the ram cylinder 15 but preventing the flow of liquid in the opposite direction.

The pump mechanism above described operates as follows: upon the up-stroke of the piston 74, the valve 89 is closed and the piston draws liquid into the lower chamber 76 through the valve 85 and port 80, and simultaneously forces the liquid in the upper chamber 77 through the port 90 and check valve 95 into the upper end of the ram cylinder 15. Upon the down stroke, liquid passes through port 81 and check valve 89 into the upper chamber 77, and since the cross sectional

area of the latter chamber is less than that of the lower chamber 76, the excess liquid is forced through the port 90 into the ram cylinder. Thus the pump is of the double action type, pumping during both strokes of the piston.

Manually control means are provided for releasing pressure in the upper end of the ram cylinder 15 and returning the liquid into the liquid reservoir 68 when it is desired to lower the jack. Such means includes a knurled control nut 93 threaded in a bore 94 at one side of the bottom plate 66 for operating a valve member 95 herein consisting of a ball, which closes a port 96 communicating with a passage 97 leading to the upper end of the ram cylinder 15. The bore 95 also has a passage 98 leading to the bottom of the reservoir 68.

In the form shown, a spring 95a is interposed between the valve member 95 and the stem of said control nut, which spring is sufficiently strong to close the check valve 95 against any pressures normally effective in the ram cylinder, when the control nut is fully screwed into the bore 94.

When it is desired to retract the ram rod into the ram cylinder for lowering the automobile, or for storing the jack away in its fully telescoped position, the control nut 93 is unscrewed a sufficient degree to open the valve port 96 and permit the fluid in the upper end of the ram cylinder to return into the reservoir 68. The rate of telescopic movement of the jack can be readily controlled by regulating the control nut, as desired.

In case any excessive pressures are generated in the ram cylinder, as for instance when the ram has reached the lower limit of its movement, the spring 95a engaging ball valve 95 operates automatically as a relief valve to permit the escape of fluid from the ram cylinder into the reservoir 68.

A horizontal disc-like plate 99 is mounted in the reservoir 68 above the flanged rim 66a of the bottom plate 66 and is provided with a plurality of relatively small apertures 100, 100 to form a baffle plate which serves to minimize the foaming of liquid adjacent the relief bore 98 and the intake port 82 during the operation of the pump. I also provide a filler plug 101 which is threaded in tap hole 102 in the top plate 67. The filler plug 101 is normally closed and sealed by a washer 103 so as to confine the operating liquid wholly within the casing 65, but said filling plug may be removed when it is desired to replenish any liquid lost by leakage.

It will be understood further from the foregoing description of the hydraulic system that the hydraulic ram, pump, and supply reservoir are all self-contained so that the jack may be used repeatedly without replenishment of liquid.

For proper operation, the reservoir 68 should be made large enough to hold sufficient liquid for filling the ram cylinder when it is in fully extended position as well as all of the operating chambers and passages of the pump, and in addition, a substantial air space should be provided for expansion above the maximum level of the liquid in the reservoir 68 so that an excessive degree of partial vacuum will not be produced in said reservoir when the ram is in its fully extended position.

Although I have shown and described a certain embodiment of my invention, it will be understood that I do not wish to be limited to the exact construction shown and described, but that various changes and modifications may be

made without departing from the spirit and scope of the invention as defined in the appended claims.

I claim:

1. In a jack, a cylindrical lifting column having a plurality of annular grooves in spaced relation therealong, a bumper catch including a supporting nut slidably mounted on said column, and an adjustable abutment member for said nut comprising a single continuous looped spring member selectively engageable in said grooves under tension, and having manually compressible terminal portions for releasing said spring member and adjusting it to another groove.

2. In a jack, a cylindrical lifting column having a plurality of annular grooves in spaced relation therealong, a bumper catch including a supporting nut slidably mounted on said column, and an adjustable abutment member for said nut comprising a looped spring member selectively engageable in said grooves under tension, and having manually compressible terminal portions for releasing said looped member at will and adjusting it selectively into another of said annular grooves, and said nut having a shoulder depending from its under face for preventing displacement of said looped member from engaging position in a proximate groove while said nut is in supporting engagement with said looped member.

3. In a jack, a cylindrical lifting column having a plurality of annular grooves in spaced relation therealong, a bumper catch including a supporting nut slidably mounted on said column, and an adjustable abutment member for said nut comprising a looped spring member selectively engageable in one of said grooves under tension, and having manually compressible terminal portions for releasing said looped member at will for adjusting it into another of said annular grooves, and said nut having a depending annular shoulder extending partially around its under face for fitting about and preventing displacement of said looped member from engaging position in a proximate groove while said nut is in supporting engagement with said looped member.

4. In a jack, a lifting column, a saddle nut thereon having a cylindrical upper bearing surface, a trunnion strap having an arched central portion engaging said bearing surface, and depending side portions with laterally extending pivotal studs thereon, said arched portion having an aperture therethrough permitting limited rocking movement of said strap on said saddle nut, and a load supporting member pivotally mounted on said studs for rocking movement on an axis transverse to the axis of rocking movement of said trunnion strap on said saddle nut.

5. In a jack, a lifting column, a saddle nut thereon having a cylindrical upper bearing surface, a trunnion strap having an arched central portion engaging said bearing surface, and depending side portions with laterally extending pivotal studs thereon, said arched portion having an aperture therethrough permitting limited rocking movement of said strap on said saddle

nut, a load supporting member pivotally mounted on said studs for rocking movement on an axis transverse to the axis of rocking movement of said trunnion strap on said saddle nut, and said trunnion strap also having retaining lugs extending inwardly from opposite side edges of said side portions at opposite ends of said nut for limiting axial movement of said nut relative to said strap.

6. In a jack, a lifting column, a saddle nut thereon having a cylindrical upper bearing surface, a trunnion strap having an arched central portion engaging said bearing surface, and depending side portions with laterally extending pivotal studs thereon, said arched portions having an aperture therethrough permitting limited rocking movement of said strap on said saddle nut, a load supporting member pivotally mounted on said studs for rocking movement on an axis transverse to the axis of rocking movement of said trunnion strap on said saddle nut, and said trunnion strap also having retaining lugs extending inwardly from opposite side edges of said side portions and extending in spaced relation below said nut, for retaining the latter loosely between said side portions.

7. In a jack, a lifting column, a saddle nut thereon having a cylindrical upper bearing surface, a trunnion strap consisting of a flat metal piece having an arched central portion engaging said bearing surface, and depending portions with laterally extending pivotal studs thereon, said arched portion having an aperture therethrough permitting limited rocking movement of said strap on said saddle nut, and a load supporting member pivotally mounted on said studs for rocking movement on an axis transverse to the axis of rocking movement of said trunnion strap on said saddle nut.

8. In a jack, a lifting column, a saddle nut thereon having a cylindrical upper bearing surface, a trunnion strap consisting of a flat metal piece having an arched central portion engaging said bearing surface, and depending portions with laterally extending pivotal studs thereon, formed integrally with said strap by punching flanged apertures in said side portions, said arched portion having an aperture therethrough permitting limited rocking movement of said strap on said saddle nut, and a load supporting member pivotally mounted on said studs for rocking movement on an axis transverse to the axis of rocking movement of said trunnion strap on said saddle nut.

EDWIN C. JUERGENS.
